UNITED STATES PATENT OFFICE.

ELBRIDGE J. STEELE, OF NEW HAVEN, CONNECTICUT, ASSIGNOR TO
SARGENT & CO., OF SAME PLACE.

DESIGN FOR A BOOT-JACK.

Specification forming part of Design No. 6,535, dated March 25, 1873.

To all whom it may concern:

Be it known that I, ELBRIDGE J. STEELE, of New Haven, in the county of New Haven and State of Connecticut, have invented a new Design for a Boot-Jack; and I do hereby declare the following, when taken in connection with the accompanying drawing and the letters of reference marked thereon, to be a full, clear, and exact description of the same, and which said drawing constitutes part of this specification, and represents a top view.

This invention relates to a design for a boot-jack to be formed from cast metal; and it consists in the peculiar configuration and ornamentation, used together or separately, as shown in the accompanying illustration.

The body A, from its end to the supports, is of an increasing width; thence, by an irregular form, as shown, to the two horns B B, the general outline of which is a continuation of the taper of the base. The surface is ornamented by a plain edge, forming a sunken panel filled with tracery, as denoted in the drawing, the ground matted or otherwise finished.

I claim as my invention—

The design for boot-jack, as herein described and shown in the accompanying illustration.

ELBRIDGE J. STEELE.
